UNITED STATES PATENT OFFICE.

FRANCIS H. HORTON, OF LONDON, ENGLAND, ASSIGNOR OF ONE-HALF TO G. N. HADEN & SONS LIMITED, OF TROWBRIDGE, WILTS, ENGLAND.

APPARATUS FOR PREVENTING WASTE OF WATER IN BATHS AND THE LIKE.

Application filed November 6, 1923. Serial No. 673,155.

To all whom it may concern:

Be it known that I, FRANCIS HERBERT HORTON, a British subject, of Lincoln House, Kingsway, London, W. C. 2, England, have 5 invented certain new and useful Improvements in Apparatus for Preventing Waste of Water in Baths and the like, of which the following is a specification, such as will enable others skilled in the art to which it 10 appertains to make and use the same.

This invention relates to apparatus for preventing the waste of water and whilst it is applicable for several such purposes it is especially designed for use with baths in 15 public wash houses or other places where, without some controlling means the water is likely to be wasted. The invention will be more particularly described in connection with baths.

20 Briefly the invention comprises a vessel connected to the bath by a water passage so arranged that the water will be the same level in both the vessel and the bath and in fitting in the vessel a float adapted to shut off the water supply when a predetermined level is reached but with the distinguishing feature that after filling to the said level the float, say a ball valve, is engaged by a catch or other device in such a manner 25 that when the vessel and bath are emptied the float will be held and no more water permitted to enter the bath until the catch or equivalent is intentionally removed and the float liberated.

30 In a general way the level of the water can be varied by an attendant and as by making the catch or equivalent adjustable.

The supply of water may be to the bath direct or to the vessel direct and find its 35 way by the before mentioned water passage from one to the other and the waste pipe may be fitted to either.

An example of the invention is shown in the accompanying drawings, in which:

40 Fig. 1 is substantially a vertical section through one of my vessels fitted with a pivoted float.

Fig. 2 is a top or plan view of the apparatus shown in Fig. 1.

45 Fig. 3 shows part of the apparatus on enlarged scale, and

50 Figs. 4 and 5 show two views of a movable slide or wedge for controlling the valve of the waste pipe and keeping the valve closed as hereinafter described.

In these drawings the vessel 1 is fitted with a water supply valve 2 having inlet at 3 and outlet at 4. This valve is opened and closed by a sliding plunger rod 5 connected by arm 6 to a bar 7 which has turning movement in the sides of the vessel at 8, 8.

The arm 6 is pinned to the bar 7 through its socket end 9 which fits over the bar. The said socket has serrations at 9^a adapted to fit to other serrations in the end of a lever 10 which carries a ball or float 11. By loosening the bar 7 and adjusting the engagement of the serrations any desired relative positions of the arm and the lever can be obtained with the result that the movement of the arm can be varied by alteration of the level of the water in that the float will rise sooner or later according to how it may be set in relation to the arm. This adjustment is facilitated by the spring shown by dotted line in the socket 9; said spring tending to disengage the teeth or serrations.

55 A second arm 12 is rigidly fixed to the bar 7 and is a loose fit at 13 in a rod 14 connected to the waste plug 15. Adjacent the upper end of this rod is a curved wedge 16 seen on a large scale in Figs. 4 and 5. This wedge catch can be turned so as to engage the under side of a roller 17 fitted to the upper end of the rod 14 and is adapted to lift the rod and open the waste pipe at 15, and will at the same time keep the arm 12 raised and the valve 2 closed.

60 In operation assuming the bath to be empty and required for use, the catch 16 is drawn back, the arm 12 is released and with the float and its lever will fall thus opening the valve 2 and closing the waste pipe. When the required level of water is reached the float will lift the rod 5 through lever 10, bar 7 and arm 6, thus closing the valve 2. To empty the bath the wedge catch is turned so as to raise the rod 14 and its waste valve 15. The arm 12 will be engaged by the lower side of the opening at 13 and will be held up thus preventing the fall of the float and reopening of the valve until the wedge catch is removed as above described.

65 What I claim is:—

1. Apparatus for preventing waste of water and for use with baths said apparatus comprising a vessel, a connection for water

- between the vessel and the bath to maintain a uniform level of liquid in said vessel and bath, a water supply valve in the vessel, a float adapted to close the valve when a predetermined level has been reached by the water and a holding means, adapted to engage the float and to releasably sustain it and thus keep the valve closed when the vessel and the bath are emptied.
- 19 2. Apparatus for preventing waste of water and for use with baths said apparatus comprising a vessel, a connection for water between the vessel and the bath to maintain a uniform level of liquid in said vessel and bath, a water supply valve in the vessel, a float adapted to close the valve when a predetermined level has been reached by the water, means for adjusting the float in relation to the valve for the purpose of altering the predetermined level of the water, and a holding means, adapted to engage the float and to releasably sustain it and thus keep the valve closed when the vessel and the bath are emptied.
- 25 3. Apparatus for preventing the waste of water and for use with baths said apparatus comprising a vessel having a water connection to the bath to maintain a uniform level of liquid in said vessel and bath, a water supply valve in the vessel, a sliding plunger controlling the said valve, a float to control the sliding plunger and through the plunger to close the valve when the water has reached a predetermined level, and a movable device adapted to support the float when the bath and vessel are emptied.
- 30 4. Apparatus for preventing the waste of water and for use with baths said apparatus comprising a vessel having a water connection to the bath to maintain a uniform level of liquid in said vessel and bath, a water
- 35 supply valve in the vessel, a sliding plunger controlling the said valve, a float to control the sliding plunger and through the plunger to close the valve when the water has reached a predetermined level, and a movable device adapted to support the float when the bath and vessel are emptied 45 50 55 60 65 70 75
5. Apparatus for preventing the waste of water and for use with baths said apparatus comprising a vessel having a water connection to the bath to maintain a uniform level of liquid in said vessel and bath, a water supply valve in the vessel, a sliding plunger controlling the said valve, a float to control the sliding plunger and through the plunger to close the valve when the water has reached a predetermined level, and a movable device adapted to support the float when the bath and vessel are emptied and to hold the waste pipe open whilst the valve is held closed. 50
6. Apparatus for preventing the waste of water from baths said apparatus comprising a vessel connected to the bath, a passage for water from the vessel to the bath, and by which the water level in the vessel and in the bath will be the same, a valve in the vessel, a float connected to the valve and adapted to close same when a predetermined water level has been reached, a device adapted to removably and simultaneously support the float and a rod controlling the waste outlet so that whilst the waste pipe is open the float is supported and the valve is kept closed.

In witness whereof I have hereunto set my hand.

FRANCIS H. HORTON.
